CLAIM

The ornamental design for a filter element of the water purifier, as shown and described.

DESCRIPTION

FIG. 1 is a perspective view of a filter element of the water purifier shown according to the present design;

FIG. 2 is a front end view thereof;

FIG. 3 is a rear end view thereof;

FIG. 4 is a left side view thereof;

FIG. 5 is a right side view thereof;

FIG. 6 is a top plan view thereof;

FIG. 7 is a bottom plan view thereof;

FIG. 8 is another perspective view thereof;

FIG. 9 is an enlarged view of part A in FIG. 2;

FIG. 10 is an enlarged view of part B in FIG. 3;

FIG. 11 is an enlarged view of part C in FIG. 4;

FIG. 12 is an enlarged view of part D in FIG. 5;

FIG. 13 is an enlarged view of the top view in FIG. 6;

FIG. 14 is an enlarged view of the bottom view in FIG. 7;

FIG. 15 is an enlarged view of part G in FIG. 1; and,

FIG. 16 is an enlarged view of part H in FIG. 8.

The portions of the drawings shown in broken lines form no part of the claimed design.
